DISCHARGE HEAD FOR FLUID CONTAINERS

Scott E. Allen, Glen Ridge, N. J., assignor to C-O-
Two Fire Equipment Company, Newark, N. J.,
a corporation of Delaware

Application November 19, 1935, Serial No. 50,615

6 Claims. (Cl. 221—73.5)

The present invention relates to discharge heads for carbon dioxide cylinders or containers holding other highly compressed fluids. Such containers are provided with a discharge port which is usually closed by a sealing disk and the disk must be punctured or cut open when it is desired to discharge the contents of the container. Usually the discharge continues until the container is emptied, but it is often desirable to stop the flow before the container has been entirely emptied. In the case of portable fire extinguishers, it is desirable for the sake of economy and also for the sake of convenience in manipulation, to stop the discharge, particularly when shifting the point of attack upon a fire from one point to another. For this reason, discharge heads for portable carbon dioxide cylinders have been provided with a manually operated valve between the sealing disk and the discharge port so as to cut off the flow at will after the sealing disk has been punctured. Such an arrangement is shown in Patent No. 1,974,254, issued September 18, 1934, in which the valve carries a tubular punch so arranged that in the act of depressing the punch to pierce the sealing disk the valve is opened.

In containers holding highly compressed fluids such as liquefied carbon dioxide, it is essential that some safety means be provided to prevent the container from bursting under excessive pressure produced by a rise of temperature above a predetermined degree. The sealing disk may be designed to burst before a dangerous pressure is reached, but with a valve blocking escape of the fluid, the sealing disk is useless as a safety valve. In the patent above referred to this difficulty is overcome by providing means to hold the valve normally in slightly open position so that should the sealing disk burst the fluid could escape past the valve and out of the normal discharge port of the discharge head.

An object of the present invention is to provide a discharge head in which the valve may be locked normally in closed position without blocking discharge of the fluid should its pressure rise sufficiently to burst the sealing disk. In a preferred embodiment of my invention a safety port is provided in the discharge head between the valve and the sealing disk and this port is normally closed by a safety disk which will burst at substantially the same pressure as that at which the sealing disk will burst, such pressure being well below that at which the cylinder itself would burst.

A further object of the present invention is

to provide a simpler and less costly construction than that disclosed in said patent.

A still further object of the invention is to provide a rotary cutter instead of the punch shown in said patent, this rotary cutter being arranged to shear a flap out of the sealing disk, leaving a portion uncut to serve as a hinge on which the flap may be bent upward into the cutter under pressure of the discharging fluid. There is a material advantage in providing a rotary cutter instead of a non-rotary punch. Less power is required to shear the disk than to puncture it. To be sure a multiplying leverage may be employed but it is desirable in a portable fire extinguisher to effect the release of the extinguishing fluid with a minimum of effort and also a minimum of manual movement. The invention has for an object to provide a device which may be operated to form a complete opening in the disk upon turning a manual controller through a comparatively small angle.

In my copending application, Serial No. 47,511, filed October 30, 1935, I disclose a rotary cutter having an extended cutting edge lying in a plane substantially normal to the longitudinal axis of the cutter and so arranged that a partial turn of the cutter will cut and score the sealing disk through the major part of a circle leaving an uncut portion on which the flap will hinge as it is forced up by the pressure of the discharging fluid. Such a cutter could be used in the discharge head shown in the present application. However, the present invention has for an object to provide a rotary cutter having a helical cutting edge so arranged as to produce a shearing cut in the sealing disk.

It is a further object of the present invention to arrange for operating a helical cutter of the type just described in such direction that the shearing point will progress from the trailing end of the cutting edge to the leading end thereof.

Other objects and advantages of my invention will appear in the following description of a preferred embodiment and thereafter the novelty and scope of the invention will be pointed out in the claims.

In the accompanying drawing:

Figure 1 is a view in vertical section through my improved discharge head;

Fig. 2 is a view in side elevation of my improved cutter in the act of making first contact with the sealing disk;

Fig. 3 is a view of the cutter after it has completed its cut and the flap has been forced up into the tubular cutter; and,

Fig. 4 is a plan view of a sealing disk showing the disk at the instant that the complete cut has been made and before the flap has been forced up by the pressure of the discharging fluid.

5 In Fig. 1 a portion of a cylinder containing highly compressed fluid is indicated at 10. This cylinder is provided with a neck 11 into which a fitting 12 is tightly screwed. This fitting is provided with a bore 13 through which the fluid in the cylinder 10 may discharge when released. The bore 13 is enlarged near its upper end and threaded to receive an annular plug 14. This plug is screwed tightly against a shoulder 15 surrounding the bore 13 at the point of enlargement of such bore. The lower end of the plug 14 carries a sealing disk 16 which normally prevents discharge of fluid from the cylinder. In order to permit of screwing the plug tightly against its seat it is provided with flutes 17 to receive a suitable key-wrench. Above the plug 14 the bore of the fitting is further enlarged to provide a lower discharge chamber 18.

The upper end of the fitting 12 is externally threaded and a tubular casing 20 is screwed thereon. This casing is formed with an annular shoulder 21 which is tightly screwed down upon the upper edge of the fitting 12 so as to form a gas tight seal between the fitting 12 and the casing 20. The bore of the tubular casing forms an extension 22 of the chamber 18. The side wall of this chamber extension 22 is of conical form and extends to an upper chamber 23 of reduced diameter. The conical wall 24 serves as a seat 35 for a plug valve 25 which when closed separates the chamber 23 from the lower chamber 22-18.

The valve 25 has a stem 26 which passes out through the upper end of the casing 20. On this valve stem there is a threaded portion 27 which engages a suitable thread in the bore of the casing so that by turning the stem the valve 25 may be lowered or raised. The projecting end of the stem 26 is provided with a hand wheel 28 for turning the same and a stuffing box 29 about the valve stem above the threaded portion thereof serves to prevent escape of fluid along the stem.

To cut open the sealing disk I provide a tubular cutter 30 which has a threaded shank 31 by which it is screwed tightly into a socket formed 50 in the valve 25. The lower end of the tubular cutter is formed with an inwardly sharpened helical cutting edge 32. The cutting end of the cutter is also formed with a recess 33 which limits the cutting edge also to an extent of about 180 degrees. This cutter, as will be explained more fully hereinafter, is arranged to cut a flap out of the disk, and the discharge of fluid takes place through the tubular cutter and thence out through lateral openings 34 into the chamber 18. Since the valve must be opened to force the cutter into cutting position the fluid will pass on into the upper chamber 23 and discharges through ports 35. These ports open through a threaded lateral tubular projection 36 to which a hose or pipe may be coupled to convey the fluid to a desired point.

Opening out of the extension 22 of chamber 18 is a safety port 38 which is normally closed by a safety disk 39 held in place by a tubular plug 40. In order to hold the valve normally in closed position the upper end of the casing 20 is provided with a lug 42 having a vertical bore therethrough to receive a pin 44 which is passed through an 75 aperture in the hand wheel 28. This aperture is

so positioned as to be aligned with the bore of the lug 42 when the valve 25 is tightly closed.

The safety feature of my invention operates as follows: The safety disk 39 is made of such strength as to rupture under a pressure substantially the same as that which will rupture the sealing disk 16 and this pressure is well below that which will cause the cylinder 10 to burst. Thus, should there be an abnormal rise of pressure in the cylinder 10 it would first burst the disk 16 permitting the fluid to discharge into the chamber 18-20 and then the disk 39 would burst permitting the fluid to escape harmlessly through the tubular plug 40. Thus, although the valve 25 remained closed there would be no danger of an explosion of the cylinder 10.

The operation of the cutter is as follows: When it is desired to discharge fluid from the cylinder 10 the locking pin 44 is removed and the hand wheel 28 is turned in the direction of the arrow to rotate the cutter and feed it downwardly into cutting engagement with the sealing disk 16. It will be observed that the valve stem has a left-hand thread 27 while the cutting edge 32 is a right-hand helix. Thus, as the cutter is turned in the direction of the arrow the lowermost point of the helix will be the trailing end and the point of shearing engagement will progress in the direction of the arrow shown in Fig. 2 from the trailing end toward the leading end. As shown in Fig. 4 the first point of engagement of the cutting edge with the disk will be at A. The parts are so proportioned that by the time the cutter has moved through 45 degrees the shearing point will have advanced to the leading end of the cutter and a cut will be made of 225 degrees, leaving 135 degrees of the complete circle uncut. However, the pressure of the fluid will force the cut portion or flap 16a upwardly and in doing so the flap will tear at each end of the cut, leaving about 45 degrees integrally connected to the body of the disk 16. Thus, with a turn of only 45 degrees after the trailing end of the cutter has begun to cut into the disk it is possible to shear out a flap 16a which will give a wide opening in the disk but which will not tear off from the disk so that there will be no danger of having a loose part carried along by the discharging fluid to jam or do damage at some point along the line.

While the angular dimensions shown in Fig. 4 illustrate a practical arrangement of parts it will be understood that my invention is not limited to the actual dimensions there given. The extent to which the disk may or should be cut will vary with different conditions but in any case the cut should be very quickly made over an arc of more than 180 degrees and yet should leave enough metal connecting the flap to the body of the disk so that the flap will not be torn off by the pressure of the escaping fluid. It is desirable to make a cut very quickly of more than 180 degrees because sealing disks are usually made of rolled sheet metal which has a definite grain in the direction of which the metal is rolled and if the cut is slowly made there is a possibility that a piece of the metal might split off in the direction of the grain under pressure of the fluid before a sufficient opening was made in the sealing disk. Such flying piece of metal might do serious damage not only in jamming passages along the line of fluid discharged but also in creating short circuits where the discharging fluid is directed upon the fire in an electrical apparatus.

It is necessary to limit the rotation of the cutter so that it will not be forced down far enough to tear off the flap. To this end the hub of the hand wheel 28 is formed with a shoulder 45 which engages a packing nut 46 of the stuffing box 29 when the cutter has been advanced to the desired limit of the cutting movement. Obviously any other suitable means may be provided for limiting the movement of the cutter.

10 While I have described a preferred embodiment of my invention I wish it to be understood that this is to be taken as illustrative and not limitative and that I reserve the right to make various changes in form, construction and arrangement 15 of parts without departing from the spirit and scope of my invention as pointed out in the following claims.

I claim:

1. A discharge head for a fluid container having a discharge port normally closed by a seal 20 rupturable by a rise of fluid pressure above a predetermined degree but below that at which the container will rupture, said head comprising a body adapted to be secured to the container over 25 said port and formed with a discharge passage for fluid released from the container, means operable at will for opening the seal to release fluid from the cylinder, a valve normally blocking said 30 passage but operable to open the passage, and safety means between the seal and valve for relieving a rise of fluid pressure above a predetermined normal.

2. A discharge head for a fluid container having a discharge port normally closed by a seal 35 rupturable by a rise of fluid pressure above a predetermined degree but below that at which the container will rupture, said head comprising a body adapted to be secured to the container over said port and formed with a discharge passage 40 for fluid released from the container, means operable at will for opening the seal to release the fluid from the cylinder, a valve normally blocking said passage but operable to open the 45 passage, a safety port opening out of the body from the passage between the valve and the seal, and a closure for said safety port rupturable at substantially the same pressure as that at which the seal will rupture.

3. A discharge head for a container holding 50 fluid under pressure, said head comprising a body formed with a passage for the discharge of fluid from the container, a sealing disk at the entrance of the passage normally preventing discharge of fluid from the container, a rotatable valve normally closing the passage, means for rotating the valve, coacting screw means on the valve and body for effecting axial movement of the valve as

it is rotated to open and close the passage, a cutter fixed to the valve and having a helical cutting edge oppositely pitched with respect to said screw means and arranged to shear a flap out of the sealing disk, a stop limiting rotation of the cutter to leave an uncut portion on which the flap may hinge as it is forced outwardly under pressure of the discharging fluid.

4. A discharge device for a container holding fluid under pressure and having a discharge port 10 closed by a sealing disk, said device comprising a tubular cutter having a helical cutting edge, means for simultaneously advancing and turning the cutter to cut the disk arcuately in such direction that the cutting point will advance along the helical edge, and a stop for limiting movement of the cutter after it has sheared out a flap in the disk having an arcuate extent of more than 180 degrees but sufficiently less than 360 15 degrees to leave an uncut portion on which the flap will hinge without tearing off as it is forced out by pressure of said fluid.

5. A discharge device for a container holding fluid under pressure and having a discharge port 20 closed by a sealing disk, said device comprising a tubular cutter having a helical cutting edge, means for simultaneously advancing and turning the cutter to cut the disk arcuately in such direction that the cutting point will advance along the helical edge, and a stop for limiting movement of the cutter after it has sheared out a flap in the disk having an arcuate extent of more than 180 degrees but sufficiently less than 360 25 degrees to leave an uncut portion on which the flap will hinge without tearing off as it is forced out by pressure of said fluid, the cutter being sharpened inwardly so that the cutting edge will coincide with the inner periphery of the tubular cutter.

6. A discharge device for a container holding 30 fluid under pressure and having a discharge port closed by a sealing disk, said device comprising a tubular cutter having a helical cutting edge and a recess limiting the cutting edge to substantially 35 180 degrees in extent, means for simultaneously advancing and turning the cutter to cut the disk arcuately in such direction that the cutting point will advance along the helical edge, and a stop for limiting the movement of the cutter after it has sheared out a flap in the disk having an arcuate extent of more than 180 degrees but sufficiently less than 360 40 degrees to leave an uncut portion on which the flap will hinge without tearing off as it is forced out by 45 pressure of said fluid.

SCOTT E. ALLEN.
